UNITED STATES PATENT OFFICE.

GEORGE WILLIAM CURTIS, OF CLEVELAND, OHIO, ASSIGNOR TO PARISH & BINGHAM COMPANY, OF CLEVELAND, OHIO, A CORPORATION OF WEST VIRGINIA.

LEVER.

No. 914,118.

Specification of Letters Patent. Patented March 2, 1909.

Application filed January 30, 1908. Serial No. 413,399.

To all whom it may concern:

Be it known that I, GEORGE WILLIAM CURTIS, a resident of Cleveland, in the county of Cuyahoga and State of Ohio, have 5 invented a new and useful Improvement in Levers; and I do hereby declare the following to be a full, clear, and exact description thereof.

My invention relates to levers and has 10 special reference to the class of levers provided with a movable dog or engaging rod thereon.

The object of my invention is to provide such a form of lever as will be light in weight, 15 easily, cheaply and quickly manufactured and will be strong and durable when in use, as well as one which will occupy a small space, and will not require any machine work.

20 My invention consists, generally stated, in the novel arrangement, construction and combination of parts, as hereinafter more specifically set forth and described and particularly pointed out in the claims.

25 To enable others skilled in the art to which my invention appertains, to construct and use my improved lever, I will describe the same more fully, referring to the accompanying drawing, in which:—

30 Figure 1 is a side elevation of my improved lever. Fig. 2 is an edge view of the same. Fig. 3 is a cross-section on the line 3—3 Fig. 1. Fig. 4 is a cross-section on the line 4—4 Fig. 1, and looking in the direction 35 of the arrow.

Like symbols of reference herein indicate like parts in each of the figures of the drawing.

As illustrated in the drawing, 1 represents 40 my improved lever which is composed of the main supporting member 2 and the movable or operating member 3. The main member 2 is formed from a plate of sheet metal cut to the size and shape required, and this plate is 45 adapted to be placed within and between suitable dies of a press in its cold state and pressed or stamped at one operation to form the complete and finished supporting member 2. This plate when placed within the 50 dies is bent up longitudinally and centrally to form the narrow U or trough shaped supporting member 2 having on its body the flat sides 4 and the curved or rounded portion 5

connecting the same, such sides having their edges 6 formed on a taper or inclined inwardly, as at 7, toward the upper end of the same from the curved or rounded connecting point 8 for the member 3, as hereinafter described, and such upper end side edges are outwardly flared, as at 9, as well as the 60 rounded portion 5, as at 10, to form the handle 11 above the flat sided body having the curved or rounded upper end 11' on said sides. The lower end of the edges 6 on the sides 4 is formed on a taper or inclined inwardly, as at 12 from the rounded or curved point 8 and terminates in the curved lower end 13 which connects with the rounded portion 5. After the member 2 has been thus formed to shape the holes 14 are punched or 70 drilled through the sides 4 for the reception of the pin 15 for supporting the lower portion of the member 3 at the connecting point 8, and holes 16 and 17 are punched or drilled through said sides for the reception of the 75 pins 18 and 19 for the connecting of the spring for the member 3 and handle for the same, as hereinafter described. Holes 20 are also punched or drilled through the sides 4 and within the curved lower end 13 for the 80 reception of a stud or pin 21 which passes through a standard 22 for the pivoting of the member 2 therein. A slot or elongated hole 23 is punched through the rounded portion 5 on the member 2 and at the lower end of the 85 same for the insertion of a quadrant 24 through the same and between the sides 4 of said member.

The handle 25 for the member 3 is formed 90 from a plate of sheet metal, cut to size and shape required, and this plate is adapted to be placed within and between suitable dies of a press in its cold state and pressed or stamped at one operation to form the complete and finished handle. This plate when 95 placed within the dies is bent up longitudinally and centrally to form substantially a U- or trough shaped handle 25 for fitting within the handle 11, having its sides and end outwardly flaring as at 26 and 27 100 respectively and the upper ends of the side edges of said sides 26 are curved or rounded to said end 27, as at 28. Lugs or projections 29 having curved or rounded ends extend out from the lower end of the side edges 26 on 105 the handle 25 and connect with the lower end

edges 30 on said handle which connect by the rounded or curved corners 31 with the ends 27 on the same. The handle 25 has holes 32 punched or drilled through the lugs 5 29 for the connecting of the handle to and within the holes 17 of said member 2 through the pin 19 fitting in said holes and holes 17 in said member, and a spiral spring 33 is connected to said handle at 34 and to and within 10 said member through the pin 18.

The movable or operating member 3 is formed from a plate of sheet metal and cut to the size and shape required having the tapered or inclined side edges 35 extending 15 inwardly from its lower to its upper end. This member 3 is adapted to fit within the member 2 and is connected thereto through a slot 36 punched or drilled in the same and fitting around the pin 15 and its lower end has 20 a shoulder 37 formed on its outer side edge 35 so that said end can engage with the notches 24' in the quadrant 24. The upper end of the member 3 is split, as at 38, and rounded or curved, as at 39, so that said split ends 25 can fit around the handle 25 and be connected thereto through a pin 40 passing through holes 41 punched or drilled in said ends and member.

A rod 42 can be connected to the member 2 30 and to the object to be moved by the lever 1 through a pin 43 passing through punched or drilled holes 44 in the sides 4 of said member and the forked end 45 on said rod fitting around said sides.

With the parts of my improved lever 1 assembled and connected together as shown, it is ready for operation and use and by 35 pressing the handle 25 toward and around the handle 11 on its pivot pin 19 in the member 2 the movable member 3 connected to said handle 25 will be raised upwardly through and within the supporting member 2 and free its lower end from its engaging notch 24' in the quadrant 24, such 40 member 3 sliding on the pin 15 in the member 3 through the slot 36 and extending the spring 33 connecting said handle 25 and said member 2. Upon the releasing of said handle 25 the tension on the 45 spring 33 will be released and allow the said handle to be thrown away from the handle 11, as well as permitting the lowering of the member 3 to allow the lower end of said member to again engage one of the notches 50 24' in the quadrant 24. By these operations, the member 3 is raised and lowered within the member 2 so that the lower end of said member 2 can engage any one of the notches 24' in the quadrant 24 and thereby 55 lock said member 2 and its connecting rod 60 42 in the position required.

It will thus be seen that in my improved lever the operating member is confined within the supporting member and will

thereby be protected from injury and the 65 elements, as well as rendering the same less liable to injury or fracture from any cause. It will be easier and more convenient to operate than the ordinary forms of these levers and will not have its operating parts 70 exposed and liable to be engaged by other objects, while at the same time the greatest strength is to be had in proportion to the weight of the same.

What I claim as my invention, and desire 75 to secure by Letters Patent, is:—

1. A lever comprising a locking member, and a supporting member formed of pressed or stamped sheet metal and in a bent U-shaped form for confining the locking member 80 therein.

2. A lever comprising a locking member, and a supporting member formed of pressed or stamped sheet metal and in a bent U-shaped form throughout its length for confining the locking member therein.

3. A lever comprising a locking member, and a supporting member formed of pressed or stamped sheet metal and having a bent U-shaped body for confining the locking 90 member therein and a bent like shaped handle portion at one end.

4. A lever comprising a locking member, and a supporting member formed of pressed or stamped sheet metal and having a bent 95 U-shaped body for confining the locking member therein and a bent like shaped outwardly flared handle portion at one end.

5. A lever comprising a locking member, and a supporting member formed of pressed 100 or stamped sheet metal and in a bent U-shaped form for confining the locking member therein and having raised portions on its side edges for the bearing point of said locking member.

6. A lever comprising a locking member, a quadrant, and a supporting member of bent U-shaped form for confining the locking lever 105 therein and having a slot therein for the reception of said quadrant.

7. A lever comprising a locking member, and a supporting member formed of pressed or stamped sheet metal and in a bent U-shaped form for confining the locking member therein and having a rounded end portion 115 thereon for the pivoting of the same.

8. A lever comprising a locking member, and a supporting member formed of pressed or stamped sheet metal and in bent U-shaped form for confining the locking member 120 therein, and a handle member formed of pressed or stamped sheet metal and having a bent U-shaped form for being connected to said members.

9. A lever comprising a locking member, 125 a supporting member formed of pressed or stamped sheet metal and in bent U-shaped form for confining the locking member

therein, and a handle member formed of pressed or stamped sheet metal and of bent U-shaped form for being connected to said locking member and having lugs or projections thereon for the connecting of the same to the supporting member.

5 In testimony whereof, I, the said GEORGE

WILLIAM CURTIS, have hereunto set my hand.

GEORGE WILLIAM CURTIS.
